CLAIM

The ornamental design for a stool, as shown and described.

DESCRIPTION

FIG. 1 is a perspective view of a stool.

FIG. 2 is a front view thereof.

FIG. 3 is a back view thereof.

FIG. 4 is a first side view thereof.

FIG. 5 is a second side view thereof.

FIG. 6 is a top view thereof; and,

FIG. 7 is a bottom view thereof.

The broken lines in the drawings illustrate portions of the stool and form no part of the claimed design.

1 Claim, 7 Drawing Sheets
